UNITED STATES PATENT OFFICE.

FREDERICK W. HEDGELAND, OF CHICAGO, ILLINOIS, ASSIGNOR TO THE
W. W. KIMBALL COMPANY, OF SAME PLACE.

SPEED-REGULATING MECHANISM FOR MUSIC-SHEETS OF AUTOMATIC INSTRUMENTS.

SPECIFICATION forming part of Letters Patent No. 614,864, dated November 29, 1898.

Application filed March 12, 1898. Serial No. 673,585. (No model.)

To all whom it may concern:

Be it known that I, FREDERICK W. HEDGELAND, a citizen of the United States, residing in Chicago, in the county of Cook and State 5 of Illinois, have invented a new and useful Improvement in Speed-Regulating Mechanism for Music-Sheets of Automatic Instruments, of which the following is a specification.

This invention has for its object the construction of a new and more practical form 10 of friction mechanism than has heretofore been used for carrying power from the wind-motor to the rolls carrying the controlling music strips or sheets employed in self-playing musical instruments and for governing the speed of the music strips or sheets.

The invention consists in the combination, with the motor and a take-up roll carrying or actuating the music - sheet, of a cone-shaped pulley receiving power from the motor and a friction-wheel bearing on the pulley and adjustably supported upon a shaft carrying motion to the take-up roll arranged parallel to the acting face of the pulley.

25 The nature of the invention and its operation will be fully understood from the description given below and the accompanying drawings, in which latter—

Figure 1 is a plan view, and Fig. 2 is a side 30 elevation, of my invention.

In said drawings, A represents the take-up roll, upon which the controlling music-sheet is wound during the playing of the instrument, and B is the music-roll from which the 35 sheet is drawn during the playing.

C represents the tracker-range.

D is a pulley which is belted to a suitable motor for operating the music-sheet. This motor is not shown, as its construction is not 40 material to the present invention. It may and preferably does operate in but one direction. The shaft D' of this pulley is supported by the blocks D², both mounted upon a plate or base D³, which is preferably pivoted 45 at one end so as to be adjustable, as herein-after specified.

Upon the shaft D' is mounted the cone-pulley E, which contacts with and drives a friction-wheel F, carried upon a shaft G, which 50 is arranged parallel and adjacent to the face of the cone-pulley. The shaft G is joined to

the roll A in such manner as to operate the latter. The wheel F is adjustable upon shaft G, so it may be moved along the face of the cone-pulley and be actuated thereby 55 at any rate of speed desired, and this adjustment may be effected in any suitable way, preferably by joining the wheel to a sleeve F', which has freedom to slide along the shaft in obedience to devices under the control of the operator—as, for instance, the rod F², joined to an elbow-lever F³, pivoted at F⁴, and actuating the sleeve through the medium of a link F⁵, pivoted to the lever at one end and having a strap F⁶, extending around the 65 enlarged end F⁷ of the sleeve and lying in the groove F⁸ formed therein.

By means of the mechanism thus far described it will be seen that the music-sheet will be operated by power from the motor and 70 that the speed with which the sheet is moved can be regulated by simply adjusting the friction-wheel F so as to bring it in contact with the large or the small part of the cone-pulley, as desired.

To make the device capable of rewinding, I employ the following: The cone - pulley is supported, as already stated, upon a movable base D³, and this movable feature is used for the purpose of destroying the contact between 80 the cone-pulley and the friction-wheel whenever any rewinding is to be done, and the result is effected by the stop rod or connection H. The end of pulley-shaft D' is joined to a stud-shaft J by a gimbal or universal joint 85 J' and rotates said shaft. The shaft J carries a pulley J², belted to another and preferably a smaller pulley J³, adapted to be clutched to the music-roll or to a connection suitable for actuating the roll by the normally open clutch shown at J⁴. When the instrument is playing, the pulleys J² and J³ rotate idly; but when the cone-pulley is shifted away from the friction-wheel the clutch J⁴ is closed by the spring J⁵ upon the 90 arm J⁶, actuated from the base D³ by any suitable means—as, for instance, the elbow-lever J⁷, pivoted at J⁸ and joined to the arm J⁶ at one end and to the pulley-base at the other end, the latter union being by means 95 of a pin J⁹ upon the base working in the slot J¹⁰ in the lever. The base of the cone-pulley 100

is pivoted at the end directly under and coincidently with the center of the gimbal-joint, the pivot not being shown. By this construction the operator is enabled to cause the re-winding of the music-sheet whenever necessary by simply operating the stop II so as to separate the friction devices and cause the engagement of the clutch J⁴, and he does this without stopping or slowing the motor or changing the direction of its movement.

I claim—

1. The combination in a self-playing instrument, of a cone-pulley driven by the motor and having a clutch connection to one of the music-sheet rolls, a friction-wheel bearing on said pulley and connected to the other roll, said pulley and wheels being separable to permit action by the clutch in rewinding, substantially as specified.
2. The combination in a self-playing instrument, of a cone-pulley driven by the motor and having a clutch connection to one of the music-sheet rolls, a friction-wheel bearing on said pulley and connected to the other roll, said pulley being movable away from the wheel to permit action by the clutch in rewinding, substantially as specified.
3. The combination in a self-playing instrument, of a cone-pulley driven by the motor

and having a clutch connection to one of the music-sheet rolls, a friction-wheel bearing on said pulley and connected to the other roll, said pulley being mounted upon a support which is movable to carry the pulley away from the wheel and which also acts to close the clutch, substantially as specified.

4. The combination in a self-playing instrument, of a cone-pulley driven by the motor and mounted upon a movable support, a pulley J² connected to said cone-pulley by a universal joint, a pulley J³ driven from pulley J², a normally open clutch for connecting pulley J³ with the music-roll, and means for closing said clutch, substantially as specified.

5. The combination in a self-playing instrument, of a cone-pulley driven by the motor and mounted upon a movable support, a pulley J² connected to said cone-pulley by a universal joint, a pulley J³ driven from pulley J², a normally open clutch for connecting pulley J³ with the music-roll, and means connecting said cone-pulley support to said clutch so that when said support is moved the clutch will be closed, substantially as specified.

FREDERICK W. HEDGELAND.
